(57) **CLAIM**

The ornamental design for a vaporizer base, as shown and described.

DESCRIPTION

FIG. 1 is a perspective view of the vaporizer base;
 FIG. 2 is a top plan view of the vaporizer base of FIG. 1,
 with the bottom plan and right side elevational views being
 the same as the top plan view of FIG. 2, and the left side
 elevational view being a mirror image of the top plan view
 of FIG. 2;

FIG. 3 is a rear elevational view of the vaporizer base of
 FIG. 1; and,

FIG. 4 is a front elevational view of the vaporizer base of
 FIG. 1.

The broken lines in the drawings illustrate portions of the
 vaporizer base that form no part of the claimed design.
